UNITED STATES PATENT OFFICE.

CHARLES MCKEEVER, OF JERSEY CITY, NEW JERSEY.

VEHICLE-LAMP.

1,252,917.

Specification of Letters Patent. Patented Jan. 8, 1918.

Application filed March 12, 1917. Serial No. 154,155.

To all whom it may concern:

Be it known that I, CHARLES MCKEEVER, a citizen of the United States, residing in Jersey City, in the county of Hudson and State of New Jersey, have invented an Improvement in Vehicle-Lamps, of which the following is the specification.

Heretofore in the construction of vehicle lamps of the class to which this invention relates, it has been customary to employ a lamp case and a reflector within the same in order to direct the rays of light in the required direction. It has also been proposed to so construct a vehicle lamp that the light and the socket in which the same is normally contained may be removed from their places in the lamp and employed for lighting purposes when making repairs to the parts of the vehicle on the road at night or at other places where a separate light is not readily available. The former feature of vehicle lamps is a matter of general common knowledge, and an instance of the latter feature is shown and described in my co-pending application, Serial No. 148,044, filed February 12, 1917.

The object of my present invention is the provision of a vehicle lamp in which the shell or casing employed is made to act not only as such, but also as a reflector, and one in which this shell is adapted to receive and contain a socket in which a light bulb is fitted at one end and a lead plug at the other end, so that the entire structure may be removably connected to a post or other support and employed for lighting when making repairs on the road or at other places, when a separate light is not available, and without removing the lamp bulb and its fixtures from the lamp shell or frame. To this end in carrying out my invention, I preferably employ a lamp shell or frame, the inner surface of which is polished or otherwise fitted to act as a reflector and which axially is provided with a tubular extension adapted to be removably connected in a post or other support. The tubular extension is also made to receive and contain a socket one end of which is constructed to hold the base of a light bulb while the other is adapted to receive a plug connecting with leads from any suitable source of electricity. The lamp made in accordance with my present invention will be hereinafter more particularly described.

In the drawing:

Figure 1 is a partial elevation and central

axial cross section of a vehicle lamp made in accordance with my present invention.

Fig. 2 is a similar view showing the parts removed from the post or other support. 60

Fig. 3 is an elevation of the lamp bulb, the socket, and the plug, showing these parts in their separate relationship.

Fig. 4 is a view similar to Fig. 1 illustrating another form of the invention, and 65

Fig. 5 is a partial plan view illustrating the manner in which the cup member is secured in position in its socket in the form of the invention shown in Fig. 4.

Referring to the drawing and more particularly to Figs. 1, 2, and 3, it will be seen that in carrying out my invention I employ a lamp shell or frame 10 which may be made of sheet metal or any other suitable material in a desired configuration and provided with a rim 11 which may be suitably attached thereto in order to hold and maintain a lens in position. The inner surface of the shell 10 is suitably polished, silvered, or otherwise finished, to act as a reflector thereby dispensing with a separate part for performing the reflector function. Axially the shell 10 is fitted with a tubular extension 12 adapted to be received in a bore 13 provided therefor in a post 14. This post 14 as will be understood, may be suitably secured in any desired position in or to a vehicle, and as herein diagrammatically illustrated, acts as a suitable support for the lamp and associated parts. 90

The outer end of the tubular extension 12 is preferably of reduced diameter thereby providing a shoulder 15 acting as a stop to determine the extent to which the tubular extension may be passed into the bore in 95 the post. As illustrated, the reduced end of this tubular extension is preferably of sufficient length to entirely fill the bore in the post; that is to say, to extend from one end thereof to the other with the shoulder 15 100 abutting against one side of the post. These parts may be secured in position in the post by means of a set screw 16 or otherwise. As will be understood, by loosening the set screw they may be readily removed from 105 their normal positions in the post.

Within the tubular extension 12 I employ a socket 17. Centrally this may be provided as illustrated with a plug 18 in which there are spring contacts 19 and 20 adapted to 110 complete the necessary electrical connections to and from the lamp bulb. This socket 17

is preferably secured in position in the tubular extension 12 by means of a set screw 21 passing through the tubular extension adjacent the point from which the same branches from the shell 10. The socket 17 at one end is slotted as indicated at 22 so as to receive the pins 23 extending laterally from the base 24 of an electric lamp bulb 25. The base 24 is adapted to be inserted 10 into this end of the socket against the yielding action of the spring contacts 20 which bear against the lamp terminals 26 when the lamp is in position to maintain the lamp in place and also to complete the electric circuit to and from the lamp filament. Similarly the opposite end of the socket 17 is slotted as indicated at 27 so as to receive the pins 28 projecting laterally from a lead plug 29 which is maintained in position by 20 means of the yielding contacts 19 bearing against the plug terminals 28' to complete the circuit to the lamp from the leads 30 connecting the plug with a suitable source of electricity.

25 As shown in Figs. 4 and 5, the shell 10 may be provided with a cup socket 31 adapted to receive the rim 32 of a cup member 33 which when in position surrounds the lamp bulb 25. This cup member, as will be 30 understood, may be made of translucent glass or other similar material so as to obviate the glare resulting from the direct rays of light from the lamp. The cup member 33 is held in position in the socket 31 by 35 means of lugs 34 provided on the rim of the socket co-acting with spaced ribs 35 having inclined surfaces on the rim of the cup member. This is clearly illustrated in Fig. 5.

From the foregoing description it will be 40 apparent that in the use of the vehicle lamp herein described the parts normally assume the positions shown in either Figs. 1 or 4 depending upon which form of the invention is employed. Also, that when necessary 45 the lamp may be removed from the post or other means of support by loosening the set screw, after having disconnected the lead plug 29, and then the lamp and asso-

ciated parts may be withdrawn from the post or other support and the lead plug 50 placed in position again as shown in Fig. 2 when the entire lamp, including of course the frame, its extension, the socket and parts connected therewith, may be employed as a light in making repairs when an independent source of light is not available. 55

I claim as my invention:

1. In a vehicle lamp and in combination, a shell having an axial extension, a support member adapted to receive the said axial extension, means adjustable exteriorly of the support for securing the axial extension in position therein, a socket member fitting within and extending through the said axial extension and adapted at its inner 65 end to receive the base of a lamp bulb and at its outer end to receive a lead plug, and means adjustable exteriorly of the axial extension and passing through the same to engage the socket member to normally secure 70 the same in position relatively to the said shell and its axial extension.

2. In a vehicle lamp and in combination, a shell having an integral axial extension, a support adapted to receive the said axial 75 extension, a set screw for securing the axial extension in position on the support, a socket member fitting within the axial extension, and a set screw for normally maintaining the socket member in position relatively 80 to the shell and its axial extension.

3. In a vehicle lamp and in combination, a shell having an integral axial extension, a support adapted to receive the said axial extension, a set screw for securing the axial 85 extension in position on the support, a socket member fitting within the axial extension, a set screw for normally maintaining the socket member in position relatively to the shell and its axial extension, a contact plug 90 fixed within the socket member, a lamp bulb adapted to be received in the inner end of the socket member, and a lead plug adapted to be secured in the outer end of the member.

Signed by me this 1st day of March, 1917. 95
CHARLES McKEEVER.
